UNITED STATES PATENT OFFICE

ELLA S. BAKER, OF KANSAS CITY, MISSOURI

DESIGN FOR AN APRON

Application filed August 26, 1929. Serial No. 32,540. Term of patent 7 years.

To all whom it may concern:

Be it known that I, ELLA S. BAKER, a citizen of the United States, residing at Kansas City, county of Jackson, State of Missouri, have invented a new, original, and ornamental Design for Apron, of which the following is a specification, reference being had to the accompanying drawing, forming a part thereof.

In the drawing:—

I claim:

The ornamental design for an apron, as shown.

ELLA S. BAKER.
